STAMPING BASE

Paul Halbig and Bruno von Zychlinski, Munich, Germany, assignors to Consortium fur Elektrochemische Industrie G. m. b. H., Munich, Germany, a corporation of Germany

No Drawing. Application December 3, 1938, Serial No. 243,898. In Germany December 7, 1937

3 Claims. (Cl. 164—58)

This invention has for its object to provide a new and improved stamping base or die counter.

These bases are used as clicker die blocks and analogous uses in which material is placed on said base and a die cuts out a piece therefrom and impinges upon the said base.

For stamping out moulded parts of material such as paper, leather, and other materials capable of being stamped, stamping bases are used, which for the most part consist of wood, but for special purposes may also consist of pulp, leather and similar substances. These stamping bases commonly possess the following disadvantages: They become so worn after only a limited period of use, that, in the case of wooden bases, they must be fitted afresh, or if they consist of leather or pulp, they must be changed.

Moreover, the above stamping bases wear the stamping tools (knives, pipes and mould gauges) very considerably which leads to a rapid blunting of the tools. Since wood is a natural material of very varying hardness (hard and soft years) sensitive stamping tools are often cracked by wooden bases, a fault which also occurs to an even greater extent in bases made of pulp. Further, the cut of the stamped out piece ceases to be sharp even when the base has only worn a little, and in the case of a soft stamping material such as textile, it loses the capacity of retaining its size.

We have found that stamping bases which contain polyvinyl alcohol or its partially saponified esters and acetals, offer special advantages. These advantages are displayed in a striking manner, e. g. in the long life of the stamping bases, in the saving of stamping tools, in the neater and sharper stamping work, even after a long period of use, and in the handiness of the bases. The stamping out process is thus considerably improved qualitatively and economically by the use of this stamping base, with regard to the stamping out tools.

The easy manipulation of our new stamping bases allows of a particularly advantageous arrangement of the plant. The preparation of the bases, also the renewal of used bases, may be readily effected, since the material may be moulded by a pressing process in a simple manner.

The material to be pressed consists of polyvinyl alcohol with a suitable water content for the moulding. Also other plastifying materials for the polyvinyl alcohol or its derivatives, such as are well known and disclosed in Patents 2,072,302 and 2,146,873, and fillers such as are well known and disclosed in Patents 1,672,157 and 2,127,896, etc., may be added. Moreover, by the addition or use of its derivatives e. g. the esters or acetals or ester acetals polyvinyl alcohol may be adapted to special requirements.

A stamping test which was carried out to determine the yield capacity of the new bases, for example after 50,000 stampings still showed good utility of the tool and base and was stopped only because the order for these particular stampings was completed. Here chrome leather belts were stamped out with a belt knife which was equipped with a cutting knife and ten tubes. To obtain the same work output with stamping bases of the usual wood, repeated changes of knife and base were necessary.

The invention claimed is:

- 30 1. A stamping base for supporting sheet material or the like containing, as the principal ingredient, a material selected from the group consisting of polyvinyl alcohol, and esters and acetals of polyvinyl alcohol.
- 35 2. A stamping base for supporting sheet material or the like containing, as the principal ingredient, partially esterified polyvinyl alcohol.
- 35 3. A stamping base for supporting sheet material or the like containing, as the principal ingredient, partially acetalised polyvinyl alcohol.

PAUL HALBIG.
BRUNO V. ZYCHLINSKI.
